TREATMENT OF HYDROCARBON OIL

John T. Ward, Westfield, N. J., assignor to Gasoline Products Company, Inc., Newark, N. J., a corporation of Delaware

Application May 31, 1933, Serial No. 673,616

4 Claims. (Cl. 196—94)

This invention relates to the art of pyrolytically treating hydrocarbon oils, more particularly crude petroleum oils containing waxy constituents of both pressable and non-pressable nature, 5 for the recovery of valuable products therefrom. Certain crude oils, for example, of the Pennsylvania and Mid-Continent types contain wax in a form readily recoverable by pressing from the distillate fraction in which it is initially recovered 10 and generally known as "crystalline wax", as well as wax which is difficult or impossible to recover by pressing from the somewhat heavier fraction in which it is found. Wax in this latter form is sometimes known as amorphous wax by reason 15 of the difficulty encountered in removing it, although actually it may be similar to or identical with wax known as crystalline wax except as to crystalline size or structure.

My invention has for an object the provision 20 of a process for the removal of a maximum amount of wax in pressable or crystalline form from a crude petroleum oil containing waxy constituents and adapted to bring wax which would ordinarily be obtained in non-pressable form into 25 pressable wax.

My invention has for further objects such further operative advantages and improvements as may hereinafter be found to obtain.

In general, my invention contemplates the distillation of crude petroleum oil containing waxy constituents under substantially non-cracking conditions and the recovery of the usual light fractions up to and including gas oil, a fraction containing at least a considerable portion of the pressable wax, and a heavier fraction, which may be a residual material, containing all or the greater portion of the amorphous or non-pressable wax and possibly also a considerable amount 40 of pressable wax not recovered in the aforesaid wax fraction.

The heavy fraction containing amorphous or non-pressable wax is subjected to moderate cracking conditions in a separate coil provided 45 for that purpose and is delivered to a separate fractionating stage, the wax fraction previously recovered from the initial fractionation stage preferably being commingled with the stream of cracked products. The separate or secondary fractionation stage is operated in such a manner 50 as to effect the condensation of all constituents up to and including such amorphous or non-pressable wax as may remain after the cracking operation. The condensates are separated into 55 various cuts, including a fraction containing the

pressable wax, one or more fractions of lighter materials, and a heavier or "slop" wax cut, while the residual products are withdrawn as fuel oil. The slop wax cut containing amorphous or non-pressable wax is preferably recycled in the cracking 5 operation to increase the yield of pressable wax.

My invention thus makes it possible to obtain a maximum yield of pressable wax by avoiding unnecessary cracking of wax initially recoverable in pressable form, while subjecting the initial yield of amorphous or non-pressable wax to an operation which tends to produce wax in pressable form and at the same time reduces to a minimum loss of lubricating oil constituents through 15 pyrolysis.

The action which takes place in the cracking coil may be either an actual conversion of amorphous wax (protoparaffin) to crystalline wax (paroparaffin) or it may be a decomposition and 20 removal of certain viscous oils or other hydrocarbon materials, the presence of which tends to hinder crystallization or separation of the true wax, and I do not limit myself to any particular theory as to the precise nature of the action which 25 takes place, but in any event the effect of the cracking in the secondary stage is to increase the yield of pressable wax and to diminish or eliminate the quantity of the yield of wax present in 30 a non-pressable form, irrespective of whether the chemical or physical nature of the wax itself has been altered in the process.

In order that my invention may be clearly set forth and understood, I now describe, with reference to the drawing accompanying and forming 35 a part of this specification, a preferred manner in which my invention may be practiced and carried out. In this drawing, the single figure is a more or less diagrammatic representation of a 40 flow sheet of a preferred form of my process.

Referring to the figure, a crude petroleum oil containing a considerable amount of waxy constituents enters the system through a conduit 1 in which is located a pump 2 and heat exchangers 3, 4, 5 and 6. The oil passes through the heat exchangers 3, 4, 5 and 6 and is then supplied in preheated form to a convection coil 7 within a furnace 8. The oil after leaving the convection coil 7 passes through a radiation coil 9 where it is brought to a suitable distillation temperature, for example, about 700° F. and preferably not over 750° F. The oil at this temperature then passes through a further convection coil 10 and leaves the furnace 8 through a 55

conduit 12 leading to the lower portion of a fractionating tower 13.

The fractionating tower 13 may be of conventional design and provided with suitable plates or trays 14 and also with an inlet 15 for superheated steam.

By means of reflux delivered to the tower 13 through conduits 16 and 17, the vapors liberated in the lower portion of the tower 13 are fractionally condensed into a plurality of fractions which are removed from the tower 13 through a corresponding plurality of outlets 20 to 25, while the residual products are withdrawn from the bottom of the tower 13 through an outlet 26. Vapors which are not condensed in the tower 13 pass through an overhead vapor line 27, through the heat exchanger 3 where they are partially cooled by indirect contact with the incoming crude oil, to a condenser 28 where they are further cooled to such an extent as to condense out substantially all constituents of a normally liquid character. The condensed products pass through a conduit 29 through a gas separator 30 from which separated gas is withdrawn through a conduit 31. A portion of the gasoline or other condensate is withdrawn from the separator 30 through an outlet pipe 31' having a pump 32 which delivers it through the conduit 16 to the upper portion of the tower 13 as reflux, while the remaining portion of the condensate is removed from the separator 30 through an outlet 33.

The various fractions ranging from naphtha to and including gas oil, which are withdrawn from the tower 13 through outlets 20 to 24, are passed to strippers 40 to 44 respectively while the fraction recovered and removed from the tower 13 through the outlet 25 is delivered to a stripper 45. The stripped products from the stripping sections 40 to 44 are withdrawn through outlets 46 to 50 and delivered to coolers 51 to 55, respectively, from which they are withdrawn for storage or for further treatment.

A portion of the oil withdrawn through one of the outlets 20 to 24, for example, refined oil, which is withdrawn from the tower 13 through the conduit 23, is taken off through a conduit 57 and after passing through the heat exchanger 4 where it gives up a portion of its heat to the incoming crude oil, is returned through a conduit 58, a pump 59 and the conduit 17 to an intermediate level in the tower 13 as reflux.

The amount and conditions of refluxing are so regulated as to make possible the recovery through the outlet 25 of a fraction containing the greater portion of the pressable or crystalline wax but substantially free from amorphous or non-pressable wax, while the residual oil removed from the bottom of the tower 13 through the conduit 26 contains substantially all of the amorphous wax as well as a small amount of pressable wax not recovered in the stream leaving the tower 13 through the conduit 25, as well as lubricating oil stock and asphaltic bottoms.

In order to effect the conversion of the amorphous or non-pressable wax in the residual oil leaving the tower 13 through the outlet 26 to pressable or crystalline wax, this hot residual oil is delivered by means of a pump 61 and the conduit 62 to a radiation coil 63 within the furnace 8 where it is brought to conditions of pressure and temperature which are effective to promote a moderate cracking of constituents of the oil, for example, a temperature of from 800° to 875° F. and a pressure of around 200 pounds per square inch. The oil then passes through a convection

coil 64 where it is maintained for a short additional period of time under these cracking conditions of temperature and pressure and then passes through a conduit 65 to an auxiliary fractionating tower 66. To the stream of partially cracked products leaving the coils 63 and 64, I preferably add the wax distillate withdrawn from the tower 13 through the outlet 25, which distillate after passing through the stripper 45 is delivered by a pump 67 through a conduit 68, through the heat exchanger 5 and a preheater 69 to the conduit 65 which serves to carry the stream of cracked products from the coil 64 to the auxiliary fractionating tower 66.

In the lower part of the fractionating tower 66 a separation of the cracked products into volatilized and non-volatilized or residual products takes place, the residual products collecting in the bottom of the tower 66 being withdrawn through a conduit 71 to be forced by a pump 72 through the heat exchanger 6 and a cooler 73. These residual products are useful as fuel oil.

During the passage of the vapors upward through the tower 66 a fractional condensation is effected by means of reflux introduced to the upper portion of the tower 66 through the conduit 14. A side stream consisting of heavy wax distillate, which contains substantially all of the pressable wax and is substantially free from non-pressable or amorphous wax, is withdrawn from the tower 66 through an outlet 75 and passes to a stripper 76, the stripped heavy wax distillate being then delivered through a conduit 77 by means of a pump 78 to a cooler 79. After leaving the cooler 79, the heavy wax distillate is withdrawn and processed in the usual manner for the recovery of wax therefrom.

A lighter fraction which may comprise a gas oil is withdrawn from a higher point in the tower 66 through an outlet 81 leading to a cooler 82, 40 while uncondensed vapors pass through an overhead line 83 and through a condenser 84 to a gas separator 85. Gas removed in the separator 85 is withdrawn through a conduit 86. A portion of the cracked distillate which is recovered in 45 the separator 85 is returned by means of a conduit 87 and pump 88 and the conduit 74 to the top of the tower 66 for use as reflux, while the remaining portion of the cracked distillate is withdrawn from the separator 85 through an 50 outlet 89.

For the purpose of removing a "slop wax" fraction containing such amorphous or non-pressable wax as is volatilized in the lower portion of the tower 66, I provide a suitable trapout tray 91, 55 the slop wax fraction being withdrawn through the trap-out tray 91 through a conduit 92 having a pump 93 and delivered through a conduit 94 to mingle with the stream of residual oil from the tower 13 which is about to enter the cracking coils 63 and 64. This recycling of the "slop wax" fraction is advantageous in that it further assists in bringing the amorphous or non-pressable wax into a crystalline or pressable condition and in reducing or eliminating the amount of non-pressable wax removed from the system, at the same time increasing the yield of pressable wax.

A vapor return conduit 95 is provided for the purpose of returning vapors from the strippers 40 to 45 to the tower 13 and a similar vapor return 70 conduit 96 is provided for the purpose of returning vapors liberated in the stripper 76 to the tower 66.

In the operation of my process the pressures maintained in the towers 13 and 66 are as low 75

as it is possible to maintain them and still accomplish the passage of the vapors therethrough. Thus the pressure on the tower 13 may be up to 50 pounds per square inch at the outlet and possibly as high as 200 pounds per square inch at the inlet, while the pressures in the tower 66 may be of the order of 50 pounds per square inch or less.

The wax distillate removed from the tower 13, which as aforesaid represents a fairly large cut of wax distillate, should ordinarily have a boiling point range of 600° to 750° F. and the outlet temperatures at the bottom of the tower 13 are ordinarily maintained at from 650° to 700° F. On the other hand, the wax distillate removed from the tower 66 through the conduits 15 and 77, due to the increase in the amount of pressable wax and the decrease in the amount of non-pressable wax may have a considerable narrower boiling point range of, for example, from 625° to 700° F.

It will be obvious to those skilled in the art, however, that such temperatures and pressures as have been given hereinabove by way of specific example may be considerably varied in accordance with the nature of the crude material treated and the results desired.

My invention is, therefore, not limited to the specific details given hereinabove by way of illustrative example but may variously be embodied within the scope of the claims hereinafter made.

I claim:

1. The process of recovering pressable wax from a crude petroleum oil containing wax constituents in pressable and non-pressable form, which comprises distilling said oil, separating the products of distillation into a fraction containing pressable wax substantially free from non-pressable wax, lighter products and heavy material containing the bulk of the non-pressable wax, subjecting said heavy material to a cracking operation to bring non-pressable wax constituents into pressable form, combining the resultant cracked products with said pressable wax fraction, and separately subjecting the volatilized portion of the mixture to fractional condensation to recover therefrom a pressable wax distillate.

2. The process of recovering pressable wax from a crude petroleum oil containing wax constituents in pressable and non-pressable form, which comprises distilling said oil, separating the products of distillation into a fraction containing pressable wax substantially free from non-pressable wax, lighter products and heavy material con-

taining the bulk of the non-pressable wax, subjecting said heavy material to a cracking operation to bring non-pressable wax constituents into pressable form, combining the resultant cracked products with said pressable wax fraction, separately subjecting the volatilized portion of the mixture to fractional condensation to recover therefrom a pressable wax distillate, and a slop wax cut containing non-pressable wax, and commingling said slop wax fraction with said heavy material for further cracking.

3. The process of recovering pressable wax from a crude petroleum oil containing wax constituents in pressable and non-pressable form, which comprises distilling said oil at a temperature of not more than 750° F., separating the products of distillation into a fraction containing pressable wax substantially free from non-pressable wax, lighter products and heavy material containing the bulk of the non-pressable wax, subjecting said heavy material to a cracking operation at a temperature of from 800° to 850° F. to bring non-pressable wax constituents into pressable form, combining the resultant cracked products with said pressable wax fraction, separately subjecting the volatilized portion of the mixture to fractional condensation to recover therefrom a pressable wax distillate and a slop wax cut containing non-pressable wax, and commingling said slop wax fraction with said heavy material for further cracking.

4. The process of recovering pressable wax from a crude petroleum oil containing wax constituents in pressable and non-pressable form, which comprises distilling said oil at a temperature of not more than 750° F., separating the products of distillation into a fraction containing pressable wax substantially free from non-pressable wax and having a boiling point range of from 600° to 750° F., lighter products and heavy material containing the bulk of the non-pressable wax, subjecting said heavy material to a cracking operation at a temperature of from 800° to 850° F. to bring non-pressable wax constituents into pressable form, combining the resultant cracked products with said pressable wax fraction, separately subjecting the volatilized portion of the mixture to fractional condensation to recover therefrom a pressable wax distillate and a slop wax cut containing non-pressable wax, and commingling said slop wax fraction with said heavy material for further cracking.

JOHN T. WARD.
